UNITED STATES PATENT OFFICE.

HENRY C. HINCHCLIFF, OF NEW YORK, N. Y.

COPY-HOLDER.

SPECIFICATION forming part of Letters Patent No. 740,652, dated October 6, 1903.

Application filed February 20, 1903. Serial No. 144,212. (No model.)

To all whom it may concern:

Be it known that I, HENRY C. HINCHCLIFF, a citizen of the United States, and a resident of New York city, borough of Brooklyn, New York, have invented certain new and useful Improvements in Copy-Holders, of which the following is a specification.

My invention relates to improvements in copy-holders adapted to hold manuscript and the like adjacent to a type-writing machine for the use of the type-writer operator and in other relations.

The object of the invention is to provide simple and efficient means for holding the copy or manuscript in position to be readily seen and to permit the lines of matter to be copied from to be readily marked off or indicated.

To these and other ends my invention contemplates the novel details of improvement that will be more fully hereinafter set forth and then pointed out in the claims.

Reference is to be had to the accompanying drawings, forming part hereof, wherein—

Figure 1 is a perspective view of a copy-holder embodying my invention. Fig. 2 is a detail view, enlarged, of part of the indicator-operating means. Fig. 3 is a section thereof on the line 3-3 in Fig. 2 looking in the direction of the arrows. Fig. 4 is a detail view, enlarged, of the gripper for operating the indicator mechanism; and Fig. 5 is a section thereof on the line 5-5 in Fig. 4 looking in the direction of the arrows.

Similar numerals of reference indicate corresponding parts in the several views.

In the drawings the base of the copy-holder is indicated generally at 1 and is shown composed of rods 2, 3, attached to a block 4, from which depends a stem 5, said parts constituting a tripod-like frame; but the base or frame may be arranged in any suitable manner. From the base 1 extends a standard or rod 6, shown attached to block 4, and at its upper portion the standard 6 carries a pulley 7, a corresponding pulley 7^a being shown carried by the stem 5, and at 8 is shown a flexible connection, which may be in the form of a chain, wire, cord, or the like passing over said pulleys, and by preference the ends of the flexible connection 8 are attached together in the manner of an endless chain or belt. The

standard 6 at its upper end is provided with a support or arm 9, attached thereto in suitable manner and adapted to carry a depending back or plate 10, against which the copy or manuscript 11 may rest. The back or plate 10 may be detachably connected with the arm 9 by bending the edge of the plate over in channel or hook form, as at 10^a, to hang upon said arm.

At 12 is indicated a suitable holder or clip for readily supporting the copy or manuscript 11 upon the back 10.

The indicator is represented at 13 and may consist of a suitable arm extending transversely across the back 10 and the copy or manuscript 11, so as to be raised and lowered in front thereof to indicate the consecutive lines of matter to be copied, and said indicator is guided vertically by the standard 6. For such purpose I have shown the indicator 13 attached to a head or block 14, provided with an aperture to receive and be guided upon the standard 6, and for the purpose of adjustment and removal of the indicator the same may be detachably connected with the block, as by means of a thumb-screw or the like 15, securing the indicator or extension 13^a thereof to the block 14 or an extension 14^a thereof. The indicator 13 and its head or block 14 are adapted to be depressed to indicate the lines of the copy by means of the flexible connection 8, and to this end the head or block 14 is shown provided with means for gripping the flexible connection 8. For this purpose the head or block 14 has a guide (shown at 16) that has a passage-way or channel 16^a, receiving one side of the flexible connection 8, (see Fig. 3,) and means are provided to connect the part 16 with the flexible connection 8, so as to sustain the indicator 13 and head or block 14 thereon and cause them to descend with the flexible connection and whereby the indicator can be readily raised. To this end I provide a pawl, dog, or the like 17, adapted to engage the flexible connection 8 and so arranged as to prevent the spontaneous descent of the indicator independently of the flexible connection 8, but to permit the indicator to be readily raised. (See Fig. 3.) The pawl or dog 17 is shown as pivotally carried upon the part 16 at 17^a and extending through an aperture 16^b therein,

and said pawl or dog is shown provided with a handle 17^b, the arrangement being such that in the normal position the pawl or dog 17 will operatively connect the part 16 with 5 the flexible connection 8, and when the indicator is to be lifted the operator can grasp the handle 17^b and raise the same, whereupon the pawl or dog will become disengaged from the connection 8, and the head or block 14 10 and the indicator 13 can be readily lifted. When the handle 17^b is released, the pawl or dog will grip the flexible connection 8 and hold the indicator in proper position.

I have provided means for intermittently 15 operating the flexible connection 8 to cause the indicator 13 to move step by step downwardly across the copy or manuscript 11 to indicate the lines to be copied. To this end I have shown a lever 18, pivotally carried by 20 the rod 3, as by a clip or bearing 19, a spring 20 serving to hold the front end of lever 18 normally raised, an adjustable stop, such as a screw 21, carried by rod 3, serving to regulate the movement of lever 18. The rear 25 end of said lever carries means for actuating the flexible connection 8, and in the arrangement shown I have provided a guide 22, secured to lever 18 and shown provided with offsets or lugs 22^a 22^b, having apertures to 30 permit the free passage of the flexible connection 8, and at 23 is indicated a pawl, spring-finger, or the like adapted to engage said flexible connection in such position that when the rear end of lever 18 is raised the 35 pawl or dog 23 will operate the connection 8 a corresponding distance, and when the lever returns to its normal position the pawl or dog 23 will slip freely down along the connection 8. Thus as the lever 18 is rocked by the 40 operator the flexible connection 8 will be given an appropriate step-by-step movement, whereby the indicator 13 will be correspondingly depressed. The lever 18 may be guided by a guide 24, carried by rod 3, or in other 45 suitable manner, if desired.

In using the copy-holder above described the operator places the copy or manuscript 11 in position, as shown, and adjusts the indicator 13 to the line to be copied, and then 50 as each line of the writing or the like is passed the operator depresses the forward end of lever 18, whereupon the flexible connection 8 will be moved around its pulleys 7 7^a corresponding distances, the side of said 55 connection to which the indicator 13 is connected by the pawl or dog 17 descending, as shown by the arrow in Fig. 1, a corresponding amount, and so on consecutively each time a line is passed. The indicator 13 may 60 be readily raised and lowered by operating pawl 17, or by merely pushing down on head or block 14 the indicator can be lowered, because in such case the flexible connection 8 will travel on the pulleys and will slip upwardly past the pawl or dog 23.

The details of construction shown and de-

scribed may be varied without departing from the spirit of my invention.

Having now described my invention, what I claim is—

1. In a copy-holder the combination of a standard, means for supporting the same, a flexible connection, and means for guiding the same, with means for operating said flexible connection, an indicator, means for guiding the same, and means for adjustably connecting said indicator with said flexible connection for permitting the indicator to be moved by or independently of said flexible connection, substantially as described. 70

2. In a copy-holder, the combination of a standard, means to support the same, a pair of pulleys, a flexible connection guided thereby, means for intermittently operating said flexible connection, an indicator, means for guiding the same, and means for connecting the indicator with said flexible connection to move the indicator downwardly thereby and to permit the indicator to be adjusted freely upwardly independently of the flexible connection, substantially as described. 85

3. In a copy-holder, the combination of a standard, means to support the same, a flexible connection, means for guiding the same, means for intermittently operating said connection, an indicator, and means for adjustably connecting the indicator with the downwardly-movable side of said flexible connection to cause the indicator to descend therewith, substantially as described. 95

4. In a copy-holder, the combination of a standard, means to support the same, a flexible connection, means to guide the same, means to intermittently operate said flexible connection, an indicator, and a pawl connected therewith arranged to engage the flexible connection to cause the indicator to descend with the latter, substantially as described. 105

5. In a copy-holder, the combination of a standard, means to support the same, a flexible connection, means to guide the same, means to operate said flexible connection, an indicator, means to guide the same, and a pawl connected with said indicator to engage said flexible connection, said pawl being provided with a handle arranged to cause the pawl to release the flexible connection when operated and to serve in permitting the indicator to be lifted, substantially as described. 110

6. In a copy-holder, the combination of a standard, means to support the same, a flexible connection, means to guide the same, an indicator, means to operate the indicator by said connection, a lever and means connected with said lever to engage one side of said connection when moving in one direction and to pass freely thereby when moving in the reverse direction, substantially as described. 120

7. In a copy-holder, the combination of a standard, means to support the same, a flexible connection, means to guide the same, an indicator, means to connect the indicator

with the downwardly-movable side of said flexible connection to cause the indicator to descend therewith, a lever, and means connected therewith to engage the upwardly-movable side of said flexible connection to operate the latter during the upstroke of said means and to permit said means to descend independently of said flexible connection, substantially as described.

10 8. In a copy-holder, the combination of a standard, means to support the same, a flexible connection, means to guide the same, an indicator, means to connect said indicator with said flexible connection, a lever, and a 15 pawl or dog connected with said lever and adapted to engage said flexible connection to thereby operate the latter in one direction of movement of the lever, substantially as described.

20 9. In a copy-holder, the combination of a standard, means to support the same, a flexi-

ble connection, means to guide the same, an indicator, means to connect said indicator with said flexible connection, a lever, a guide carried by said lever adjacent to one side of 25 said flexible connection, and a pawl also carried by said lever to operate said flexible connection, substantially as described.

10. In a copy-holder, the combination of a standard, means to support the same, a flexible connection, means to guide the same, a head or block guided by said standard, an indicator connected with said head or block, means for connecting said indicator with said flexible connection, and means for intermittently operating said flexible connection to cause the indicator to descend, substantially as described.
